UNITED STATES PATENT OFFICE

2,100,350

MINING APPARATUS

Charles F. Osgood, Claremont, N. H., assignor to
 Sullivan Machinery Company, a corporation of
 Massachusetts

Application January 2, 1936, Serial No. 57,156

32 Claims. (Cl. 262—28)

This invention relates to mining apparatus, and more particularly to an improved coal mining apparatus of the wheel mounted, track cutter type having an improved adjustable supporting structure for the kerf cutter.

An object of this invention is to provide an improved coal mining apparatus of an improved construction whereby the coal may be cut in an improved manner. Another object is to provide an improved coal mining apparatus of the wheel mounted, track cutter type. A further object is to provide an improved adjustable supporting structure for the kerf cutter of such an apparatus, together with improved means for adjusting the cutter supporting structure. Yet another object is to provide an improved swinging arm structure and tiltable cutter support for adjusting the kerf cutter, together with improved means for swinging the arm structure and for tilting the cutter support. Another object is to provide an improved coal mining apparatus having a novel arrangement of parts and improved features of construction. These and other objects will, however, hereinafter more fully appear in the course 25 of the ensuing description and as more particularly pointed out in the appended claims.

In the accompanying drawings there are shown for purposes of illustration one form and a modification thereof which the invention may assume 30 in practice.

In these drawings,—

Fig. 1 is a plan view of a coal mining apparatus having embodied therein one illustrative form of the invention.

Fig. 2 is a side elevational view of the mining apparatus shown in Fig. 1.

Fig. 3 is an enlarged view in longitudinal section taken substantially on line 3—3 of Fig. 1.

Fig. 4 is an enlarged view in longitudinal section taken substantially on line 4—4 of Fig. 1.

Fig. 5 is a horizontal sectional view taken substantially on line 5—5 of Fig. 3.

Fig. 6 is a detail sectional view showing the locking cylinders and the control valve therefor.

Fig. 7 is a fragmentary side elevational view of the forward portion of the mining apparatus shown in Fig. 2 illustrating a modified form of locking means.

Fig. 8 is a diagrammatic view of the hydraulic fluid system.

In this illustrative embodiment of the invention, there is shown a coal mining apparatus of the wheel mounted, track cutter type adapted to operate while supported and guided by a mine track-way, although it will be evident that various fea-

tures of the invention may be incorporated in mining apparatus of various other types.

Referring to the drawings, and more particularly to the form of the invention shown in Figs. 1 to 6, inclusive, and Fig. 8, it will be noted that there is shown a portable base 1 herein in the form of a truck mounted on wheels 2 adapted to run along a mine trackway 3 laid on the mine floor. Mounted on the forward portion of the truck frame is a horizontal turntable 4 rotatable about a vertical axis and journaled on a bearing annulus or ring 5 supported by an annular frame 6 secured to the upper portion of the truck frame. The turntable has an integral cylindrical bearing post 7 journaled in bearing sleeves 8 and 9, the former being supported within annular bearing supports 10 secured to the upper portion of the truck frame, while the latter is supported within a cylindrical bearing support 11 supported within the lower portion of the truck frame. Secured to the lower end of the bearing post 7 is a retaining plate 12, while interposed between this plate and the lower surface of the truck frame is a bearing washer 13. In this illustrative construction, formed integral with the turntable is a rigid horizontal arm 14 overhanging the forward end of the truck frame and supporting at its outer extremity a depending annular frame portion 15 in which is supported bearing sleeves 16. Journaled within these bearing sleeves for rotation about a horizontal axis extending radially with respect to the turntable axis is a cylindrical neck frame 17 formed integral with a rotatable head frame 18. Secured to the cylindrical bearing portion of the rotatable head frame 18 is a retaining ring 19 for maintaining the rotatable head frame in position within the cylindrical frame portion 15 of the turntable arm. Pivotally mounted on a transverse pivot pin 20 supported within the forwardly projecting sides 21 of the rotatable head frame is an elongated arm structure or boom 22, the axis of pivotal movement of the arm structure being arranged at right angles to the axis of rotation of the head frame 18. This arm structure has a yoke-shaped frame 23 provided at the rear ends of the yoke arms, with trunnions 24 journaled on the pivot pin 20, while secured to the forward end of the yoke-shaped frame 22 is a forwardly projecting arm frame 25 on the outer extremity of which is pivotally mounted at 26 a tiltable cutter support 27 for supporting a kerf cutter 28. The kerf cutter is herein in the form of an elongated plane cutter bar 29 carried by a hanger frame 30, and mounted for circulation about the margin of the cutter 55

bar is an endless cutter chain 31. The bar hanger 30 is secured to an annular bearing frame 32 journaled in a bore 33 formed in the frame of the cutter support and retained in the bore by 5 means of a retaining ring 34 secured to the cutter support frame, the cutter bar being mounted for pivotal movement about an axis at right angles to the pivotal axis of the tiltable support and the arm structure pivot axis. Supported at the rear 10 end of the arm structure 22 is a motor 35 having its power shaft 36 extending longitudinally of the arm structure, and fixed to the forward end of the motor power shaft is an element of a coupling 37 for connecting an alined shaft 38 with the 15 motor shaft. The shaft 38 is suitably journaled within the arm structure and has keyed thereto at its forward end a bevel gear 39 meshing with a bevel gear 40 journaled on a transverse shaft 41 alined with the cutter support pivot and on 20 which the cutter support is pivotally mounted, the shaft being supported within parallel projections 42 of the arm frame 25. Meshing with and driven by the bevel gear 40 is a bevel gear 43 fixed to a shaft 44 suitably journaled within 25 the frame of the tiltable cutter support 27. Fixed to and driven by the shaft 44 is a bevel gear 45 meshing with a bevel gear 46 connectible by a sliding clutch 47 to a shaft 48 herein suitably journaled within the frame of the cutter support 30 and arranged with its axis alined with the cutter bar pivot axis. Keyed to the shaft 48 is a chain sprocket 49 which engages and drives the endless cutter chain 31. It will thus be seen that irrespec- 35 tive of the adjusted position of the arm structure and cutter support about their pivotal axes, the cutter chain may be driven by the motor 35 and that the cutter chain may remain stationary during running of the motor by disconnecting the sliding clutch 47.

40 A motor 50 herein of the hydraulically operated reversible type is arranged within the frame of the cutter support 27 and the power shaft 51 of this motor has keyed thereto a spur gear 52 meshing with a large internal gear 53 formed integral with the cylindrical bearing support 32 for the cutter bar hanger. It will thus be seen that the cutter bar may be swung about its pivot relative to the cutter support in either of opposite directions, depending upon the direction of rotation of the motor 50, and the liquid may be trapped in the motor to lock the cutter bar in its 45 adjusted position about its pivot.

50 Now referring to the improved means for swinging the arm structure about its pivot relative to the rotatable head frame and for tilting the cutter support relative to the arm structure, it will be noted that pivotally mounted at 55 within the projecting portions 21, 21 of the rotatable head frame is a pair of hydraulic cylinders or rams 56 each containing a reciprocable piston 57 having its piston rod 58 extending forwardly through the packed front head 59 of the cylinder, and the forward extremities of the piston rods are pivotally connected at 60 to projections 61 formed integral 55 with the frame of the tiltable cutter support. Means is provided for locking the arm structure to the head frame during tilting of the cutter support and for locking the cutter support to the arm structure during swinging of the arm structure about its pivot relative to the rotatable head frame. This locking means preferably comprises, as shown in Fig. 6, a pair of hydraulic locking cylinders 62 and 63, each containing a reciprocable piston 64 having a piston rod 65 guided within 60 a bracket 66 secured to the arm structure. The

outer extremity of each piston rod is provided with a locking extremity or plunger 67 engageable with locking recesses 68, 68 formed respectively on the rotatable head frame and the frame of the tiltable cutter support. The pistons 64 are constantly urged toward their locking position by means of coil springs 69 and a valve 70 is provided for controlling the flow of liquid pressure to the cylinders to effect release of the locking plungers, in a manner to be later described. This valve 10 has an operating lever 71 provided with usual detent means for holding it in its different positions. The means for rotating the turntable 4 and the head frame 18 about their respective axes comprises a pair of hydraulic cylinders or rams 75, 75, 15 each containing a reciprocable piston 76. The cylinders are mounted within the truck frame and arranged in parallel relation on axes extending longitudinally of the truck frame, and spaced equi-distantly from the longitudinal vertical 20 center of the truck as shown in Fig. 5. These cylinders are provided with front heads 77 attached to the truck frame, and the pistons have piston rods 78 extending rearwardly through the packed rear heads 79 of the cylinders. Secured to the rear ends of the piston rods are brackets 80, each having journaled thereon a cable guiding pulley 81. Journaled coaxially with and rotatable relative to the turntable 4 beneath the latter is a large guide sheave or pulley 82, while arranged at the rear of the guide sheave 82 is a horizontal guide pulley 83. Supported by brackets 84 at the opposite sides of the cylindrical bearing portion 15 are inclined guide pulleys 85, 25 while secured to the rotatable head frame and surrounding the head frame axis is a cable drum 86. A pair of cables 87, 87 are fixed at one end to the truck frame, and these cables pass around the guide pulleys 81 and then rearwardly around the opposite sides of the guide pulley 83 and about 30 the opposite sides of the large guide sheave 82, over the guide pulleys 85 and around the cable drum 86, the opposite ends of the cables being fixed to the cable drum 86. The means for locking the rotatable head frame against rotation 35 during turntable rotation comprises a locking pin 88 guided within a bracket 89 mounted on the turntable and having an operating lever 90. This locking pin is adapted to project within locking recesses 91 formed in the rotatable head frame 40 so that when one of these locking recesses registers with the pin, the pin may be slid inwardly to lock the head frame against rotation. The turntable 4 is provided with a similar locking pin 92 guided on the truck body and having an operating lever 93 so that the turntable will be locked 45 against rotation during rotation of the head frame. From the foregoing, it will be evident that when hydraulic pressure is supplied to the front 50 end of one or the other of the cylinders 75, 75, the turntable and head frame may be selectively 55 rotatable about their respective axes in one direction or the other, depending upon which cylinder is operated. As shown in Fig. 3, supported within 60 the truck frame is a hydraulic motor 95 of the reversible type having its power shaft connected to a longitudinal transmission shaft 96, herein journaled within axle housings 97 secured to the truck frame. Arranged within the axle housings and 65 fixed to the shaft 96 are worms 98 meshing with worm wheels 99 keyed to the truck wheel axles 100. When hydraulic pressure is supplied to the motor 95, the truck wheels may be driven at any 70 desired speed and in either of opposite directions. 75

When liquid is trapped within the motor 95, the truck wheels may be locked against rotation.

Now referring to the means for supplying pressure to the various hydraulic devices, it will be noted that supported by the truck frame is a motor 102 having its power shaft 103 connected to the motor shaft of a gear pump 104. This gear pump is submerged in liquid, preferably oil, contained within a tank 105 supported by the truck frame. As shown in Fig. 8, the discharge side of the pump is connected through a conduit 106 to the intake passage of a valve box 107, the discharge passages of the valve box being connected through branched conduits 108, 108 to a conduit 109 leading to the tank. Contained in the valve box are slide valves of the conventional balanced type 110, 111, 112, and 113, and these valves are adapted to control the supply of liquid pressure to the various hydraulic cylinders and the hydraulic motors. The valve 110 controls the supply of liquid pressure through conduits 114, 114 to the forward ends of the cylinder 75, while the rear ends of these cylinders are connected through conduits 115, 115 to a conduit 116 leading to the tank for conducting oil leakage back to the tank. The valve 111 controls the flow of liquid pressure through conduits 117, 118 to the hydraulic truck wheel driving motor 95. The valve 112 controls the supply of liquid pressure through a conduit 119 and branched conduits 120, 120 to the rear ends of the cylinders 56, and through a conduit 121 and branched conduits 122, 122 to the forward ends of the cylinders 56. The valve 113 controls the flow of liquid pressure through conduits 123, 124 to the hydraulic motor 50. Conduits 123, 124, 125 connect the intake passage of the valve box to the control valve 70 for the hydraulic lock cylinders 62, 63, while a conduit 126 connects the valve 70 to the discharge passage of the valve box. Conduits 127 and 128 connect the valve 70 with the lock cylinders 62, 63. It will thus be seen that when the valve 70 is in the position shown in Fig. 8, hydraulic pressure may flow through the conduit 125, through a passage in the valve and through conduits 127, 128 to the lock cylinders 62, 63. When the position of the valve 70 is reversed the conduits 127, 128 will be connected to the discharge conduit 126. By suitably positioning the valve 70, hydraulic pressure will be supplied to one of the lock cylinders, while the other lock cylinder is connected to the discharge conduit.

In Fig. 7 there is shown a modified form of locking means for the arm structure and cutter support, wherein the locking means is mechanically operated. This locking means comprises locking plungers 130 and 131 guided in brackets 132 attached to the side of the arm structure. These plungers are engageable with locking recesses 133 formed on the head frame and cutter support, in the manner shown. Secured to the plungers are rods 134 and 135, respectively, each formed at its inner end for engagement with a rotatable cam 136 mounted on the arm structure. Coil springs 137 surrounding these rods and engaging collars 138 fixed to the rods urge the plungers toward their released position. The cam 136 has an operating lever 139 provided with usual detent means for holding it in its different positions. When the cam is in the position shown in Fig. 7, both plungers are held in locking engagement with a locking recess so that both the arm structure and cutter support are locked against pivotal movement. When the cam is turned through 90° in one direction or the

other, one of the plungers is maintained connected while the other is released by its coil spring. It will be evident that if desired the locking plungers and cooperating recesses may be substituted with contractible brake bands engaging braking surfaces on the head frame and cutter support for yieldingly locking the arm structure and cutter support against swinging movement. 5

The mode of operation of the improved mining apparatus will be clearly apparent from the description given. The apparatus may be propelled along the mine trackway at any desired speed by the hydraulic motor 95 driving the truck wheels, this motor being reversible to enable 10 propulsion of the apparatus in either direction along the mine trackway. The turntable may be rotated to swing the arm structure horizontally about the turntable axis by means of hydraulic cylinders 75, 75 under the control of the slide 15 valve 110, and these same cylinders may be operated to rotate the head frame about its axis with respect to the turntable to move the kerf cutter into either horizontal or vertical cutting 20 position. The arm structure and cutter support 25 may be swung about their respective pivots by the hydraulic cylinders 56 under the control of the slide valve 112, and the cutter bar may be swung about its pivot relative to the cutter support in either of opposite directions at the desired 30 speed by the hydraulic motor 50 controlled by the slide valve 113. By adjusting the turntable, rotating the head frame, and swinging the arm structure, and cutter support, the kerf cutter may be positioned to cut kerfs in the coal face 35 at any desired location between ribs, between the mine roof and mine floor, and in either rib, in the manner well understood by those skilled in the art. 40

As a result of this invention it will be noted 45 that an improved mining apparatus is provided having an improved adjustable supporting structure for the kerf cutter, and improved adjusting means for the supporting structure whereby the kerf cutter may be positioned at any desired location with respect to the work in an improved manner. It will further be evident that by the provision of the separate locking means for the arm structure and cutter support, and by the improved arrangement of the parts disclosed, it 50 is possible by means of but a single pair of hydraulic cylinders to effect swinging of the arm structure and tilting of the cutter support about its pivot relative to the arm structure. Further, by the provision of hydraulic variable speed driving motors for the truck wheels and kerf cutter, the apparatus may be propelled along the mine trackway and the kerf cutter swung about its pivot at any desired speed, in an improved manner. Other uses and advantages of the improved mining apparatus will be clearly apparent 55 to those skilled in the art. 60

While there are in this application specifically described one form and a modification thereof which the invention may assume in practice, it 65 will be understood that this form and modification are shown for purposes of illustration and that the invention may be further modified and embodied in various other forms without departing from its spirit or the scope of the appended claims. 70

What I claim as new and desire to secure by Letters Patent is:

1. In a mining apparatus, a swinging arm structure, a cutter support pivotally mounted on 75

said arm structure, a kerf cutter carried by said cutter support, and common motor operated devices having common final terminal elements through which arm structure swing and cutter support tilt are effected for swinging said arm structure and for tilting said cutter support about its pivot relative to said arm structure to move said kerf cutter into parallel cutting planes, said devices operative to effect swinging of said arm structure while said cutter support remains stationary as regards swinging movement about its pivot relative to said arm structure.

2. In a mining apparatus, a swinging arm structure, a cutter support pivotally mounted on said arm structure with its pivot axis parallel to the axis of arm structure swing, and a pair of hydraulic cylinders, each common to arm structure swinging and cutter support tilting, connected to said cutter support, for swinging said arm structure and for tilting said cutter support about its pivot relative to said arm structure.

3. In a mining apparatus, a swinging arm structure, a cutter support pivotally mounted on said arm structure, a kerf cutter carried by said support, common motor operated devices operable both for swinging said arm structure and for tilting said cutter support about its pivot relative to said arm structure to move said kerf cutter into parallel cutting planes, and devices separate from said motor operated devices for locking said arm structure against swinging movement about its pivot during tilting of said cutter support and for locking said cutter support to said arm structure during swinging of the latter about its pivot.

4. In a mining apparatus, a support, a swinging arm structure pivotally mounted on said support, a cutter support pivotally mounted on said arm structure, a kerf cutter carried by said cutter support, and common motor operated devices extending between said first support and said cutter support having common final terminal elements through which arm structure swing and cutter support tilt are effected for swinging said arm structure about its pivot and for tilting said cutter support about its pivot relative to said arm structure to move said kerf cutter into parallel cutting planes, said devices operative to effect swinging of said arm structure while said cutter support remains stationary as regards swinging movement about its pivot relative to said arm structure.

5. In a mining apparatus, a support, a swinging arm structure pivotally mounted on said support, a cutter support pivotally mounted on said arm structure, a kerf cutter carried by said cutter support, common motor operated devices extending between said first support and said cutter support and operable both for swinging said arm structure about its pivot and for tilting said cutter support about its pivot relative to said arm structure to move said kerf cutter into parallel cutting planes, and means separate from said motor operated devices for locking said arm structure to said first support during swinging of said cutter support and for locking said cutter support to said arm structure during swinging of the latter about its pivot relative to said first support.

6. In a mining apparatus, a rotatable head frame, a swinging arm structure pivotally mounted on said head frame, a cutter support pivotally mounted on said arm structure, and common motor operated devices extending between said head frame and said cutter support

and having common final terminal elements through which arm structure swing and cutter support tilt are effected for swinging said arm structure and for tilting said cutter support about its pivot relative to said arm structure, said devices operative to effect swinging of said arm structure while said cutter support remains stationary as regards swinging movement about its pivot relative to said arm structure. 5

7. In a mining apparatus, a rotatable head frame, a swinging arm structure pivotally mounted on said head frame, a cutter support pivotally mounted on said arm structure, and hydraulic cylinder and piston devices extending between and each connected both to said head frame and to said cutter support for swinging said arm structure and for tilting said cutter support about its pivot relative to said arm structure.

8. In a mining apparatus, a rotatable head frame, a swinging arm structure pivotally mounted on said head frame, a cutter support pivotally mounted on said arm structure, hydraulic cylinder and piston devices extending between said head frame and said cutter support for swinging said arm structure and for tilting said cutter support about its pivot relative to said arm structure, said devices common to both functions, and means for locking said arm structure against swinging movement relative to said head frame during tilting of said cutter support and for locking said cutter support to said arm structure during swinging of the latter relative to said head frame. 20 25 30

9. In a mining apparatus, a swinging arm structure, a cutter support pivotally mounted on said arm structure, locking devices mounted on said arm structure for locking said arm structure against swinging movement about its pivot and for locking said cutter support to said arm structure, and means mounted on said arm structure 35 40 for simultaneously or separately operating said locking devices, and for precluding simultaneous release of said locking devices, said operating means always maintaining said locking device for said arm structure in locking position during 45 swinging of the cutter support about its pivot relative to said arm structure and vice versa.

10. In a mining apparatus, a swinging arm structure, a cutter support pivotally mounted on said arm structure, locking devices mounted on said arm structure for locking said arm structure against swinging movement about its pivot and for locking said cutter support to said arm structure, means mounted on said arm structure for simultaneously or separately operating said locking devices and for precluding simultaneous release of said locking devices, said operating means always maintaining said locking device for said arm structure in locking position during swinging of the cutter support about its pivot relative 50 55 60 to said arm structure and vice versa, and means for swinging said arm structure about its pivot when its locking device is released and said cutter support locking device is connected.

11. In a mining apparatus, a swinging arm structure a cutter support pivotally mounted on said arm structure, locking devices mounted on said arm structure for locking said arm structure against swinging movement about its pivot and for locking said cutter support to said arm structure, means mounted on said arm structure for simultaneously or separately operating said locking devices and for precluding simultaneous release of said locking devices, and common means connected to said cutter support and common to 65 70 75

both arm structure swing and cutter support tilt for swinging said arm structure about its pivot when its locking device is released and said cutter support locking device is connected and for tilting 5 said cutter support about its pivot relative to said arm structure when its locking device is released and said arm structure locking device is connected.

12. In a mining apparatus, a swinging arm 10 structure, a cutter support pivotally mounted on said arm structure, hydraulic locking devices mounted on said arm structure for locking the latter against swinging movement during tilting of said cutter support about its pivot relative to 15 said arm structure and for locking said cutter support to said arm structure during swinging of the latter about its pivot, and valve means mounted on said arm structure for effecting simultaneous or separate operation of said locking devices.

20 13. In a mining apparatus, a swinging arm structure, a cutter support pivotally mounted on said arm structure, hydraulic locking devices mounted on said arm structure for locking the latter against swinging movement during tilting 25 of said cutter support about its pivot relative to said arm structure and for locking said cutter support to said arm structure during swinging of the latter about its pivot, valve means mounted on said arm structure for effecting simultaneous or

30 separate operation of said locking devices, and hydraulically operated means for swinging said arm structure about its pivot when its locking device is released and said cutter support is locked to said arm structure and for tilting said 35 cutter support relative to said arm structure when its locking device is released and said arm structure is locked against swinging movement by its locking device.

14. In a mining apparatus, a portable base, a 40 horizontal turntable on said base, a support mounted on said turntable for rotation with respect thereto about a horizontal axis, an arm pivotally mounted on said support to swing relative thereto, a cutter support pivotally mounted 45 on the outer extremity of said arm, a kerf cutter pivotally mounted on said cutter support to swing relative thereto, and hydraulically operated devices for rotating said turntable relative to said base, for rotating said support relative to said 50 turntable for swinging said arm relative to said support, for tilting said cutter support relative to said arm and for swinging said kerf cutter about its pivot relative to said support, said hydraulic devices for swinging said arm and tilting said 55 cutter support being common to both functions and said cutter support always remaining stationary as regards tilting movement relative to said arm during swinging of the latter.

15. In a mining apparatus, a portable base, a 60 horizontal turntable on said base, a support mounted on said turntable for rotation with respect thereto about a horizontal axis, an arm pivotally mounted on said support to swing relative thereto, a cutter support pivotally mounted 65 on the outer extremity of said arm, a kerf cutter pivotally mounted on said cutter support to swing relative thereto, hydraulically operated devices for rotating said turntable relative to said base, for rotating said support relative to said turntable, for swinging said arm relative to said support, for tilting said cutter support relative to said arm and for swinging said kerf cutter about its pivot relative to said support, said hydraulic devices for swinging said arm and tilting said 70 cutter support being common to both functions

and said cutter support always remaining stationary as regards tilting movement relative to said arm during swinging of the latter, and hydraulically operated devices for propelling the apparatus.

16. In a mining apparatus, an adjustable member, a cutter support pivotally mounted on said adjustable member for tilting movement with respect thereto, a kerf cutter carried by said cutter support, and hydraulic cylinder and piston devices for adjusting said member and for tilting said cutter support relative to said member to move said kerf cutter into parallel cutting planes, said devices common to both adjustment of said member and tilting of said cutter support. 15

17. In a mining apparatus, a support, an arm pivotally mounted on said support to swing with respect thereto, a cutter support rotatably mounted on the outer extremity of said arm, said cutter support having a projecting frame 20 portion, a kerf cutter carried by said cutter support, and an adjusting device extending between said first support and said projecting frame portion and pivotally connected thereto for swinging said arm relative to said first support and for 25 tilting said cutter support relative to said arm to move said kerf cutter into parallel cutting planes.

18. In a mining apparatus, a frame, a supporting structure pivotally mounted on said frame to swing with respect thereto, a cutter support pivotally mounted on said supporting structure to tilt relative thereto about an axis parallel with the pivotal axis of said supporting structure, a plane kerf cutter carried by said cutter support, 30 and means common both to swinging of said supporting structure and tilting of said cutter support and embodying extensible adjusting devices extending between said frame and said cutter support for swinging said supporting structure 35 and tilting said cutter support to move said kerf cutter into parallel cutting planes. 40

19. In a mining apparatus, a frame, a supporting structure pivotally mounted on said frame to swing with respect thereto, a cutter support pivotally mounted on said supporting structure to tilt relative thereto about an axis parallel with the pivotal axis of said supporting structure, a plane kerf cutter carried by said cutter support, and means embodying extensible adjusting devices extending between and each connected at 45 its opposite extremities to said frame and said cutter support for swinging said supporting structure and tilting said cutter support to move said kerf cutter into parallel cutting planes, said 50 swinging means also embodying means for locking said cutter support against tilting movement about its pivotal axis relative to said supporting structure during swinging of the latter. 55

20. In a mining apparatus, a frame, a supporting structure pivotally mounted on said frame to swing with respect thereto, a cutter support pivotally mounted on said supporting structure to tilt relative thereto about an axis parallel with the pivotal axis of said supporting structure, a 65 plane kerf cutter carried by said cutter support, and means embodying extensible adjusting devices extending between said frame and said cutter support and common both to supporting structure swing and cutter support tilt for swinging said supporting structure and tilting said cutter support to move said kerf cutter into parallel cutting planes, said swinging and tilting means also embodying means for locking said cutter support against tilting movement about 70 75

its pivotal axis relative to said supporting structure during swinging of the latter and for locking said supporting structure against swinging movement about its pivotal axis relative to said frame 5 during tilting of said cutter support.

21. In a mining apparatus, a revoluble frame mounted for rotation about a horizontal axis, a supporting structure pivotally mounted on said frame to swing with respect thereto, a cutter support pivotally mounted on said supporting structure to tilt relative thereto about an axis parallel with the pivotal axis of said supporting structure, a plane kerf cutter carried by said cutter support, and means embodying extensible 10 adjusting devices extending between and each connected at its opposite extremities to said revoluble frame and said cutter support for swinging said supporting structure and tilting said cutter support to move said kerf cutter into 15 parallel cutting planes in any position of said 20 parallel cutting planes in any position of said revolving frame about its axis of rotation.

22. In a mining apparatus, a revoluble frame mounted for rotation about a horizontal axis, a supporting structure pivotally mounted on said 25 frame to swing with respect thereto, a cutter support pivotally mounted on said supporting structure to tilt relative thereto about an axis parallel with the pivotal axis of said supporting structure, a plane kerf cutter carried by said 30 cutter support, and means embodying extensible adjusting devices extending between said revoluble frame and said cutter support and each common both to supporting structure swing and cutter support tilt for swinging said supporting 35 structure and tilting said cutter support to move said kerf cutter into parallel cutting planes in any position of said revolving frame about its axis of rotation, said swinging means also embodying means for locking said cutter support 40 against tilting movement about its pivotal axis relative to said supporting structure during swinging of the latter.

23. In a mining apparatus, a revoluble frame mounted for rotation about a horizontal axis, a supporting structure pivotally mounted on said 45 frame to swing with respect thereto, a cutter support pivotally mounted on said supporting structure to tilt relative thereto about an axis parallel with the pivotal axis of said supporting 50 structure, a plane kerf cutter carried by said cutter support, and means embodying extensible adjusting devices extending between and each connected at its opposite extremities to said revoluble frame and said cutter support for swinging 55 said supporting structure and tilting said cutter support to move said kerf cutter into parallel cutting planes in any position of said revolving frame about its axis of rotation, said swinging and tilting means also embodying means for locking 60 said cutter support against tilting movement about its pivotal axis relative to said supporting structure during swinging of the latter and for locking said supporting structure against swinging movement about its pivotal axis relative to said frame during 65 said frame during tilting of said cutter support.

24. In a mining apparatus, a frame, a supporting structure pivotally mounted on said frame to swing in a vertical direction with respect thereto, a cutter support pivotally mounted on said 70 supporting structure to tilt relative thereto about an axis parallel with the supporting structure swing axis, a horizontal plane kerf cutter carried by said cutter support, and means embodying extensible adjusting devices extending between said 75 frame and said cutter support and common to

supporting structure swing and cutter support tilt for swinging said supporting structure and tilting said cutter support about their respective pivotal axes to move said kerf cutter into parallel horizontal cutting planes at different elevations. 5

25. In a mining apparatus, a frame, a supporting structure pivotally mounted on said frame to swing in a vertical direction with respect thereto, a cutter support pivotally mounted on said supporting structure to tilt relative thereto about 10 an axis parallel with the supporting structure swing axis, a horizontal plane kerf cutter carried by said cutter support, and means embodying extensible adjusting devices extending between and each connected at its opposite extremities to 15 said frame and said cutter support for swinging said supporting structure and tilting said cutter support about their respective pivotal axes to move said kerf cutter into parallel horizontal cutting planes at different elevations, said swinging 20 means also embodying means for locking said cutter support against tilting movement about its pivotal axis relative to said supporting structure during swinging of the latter. 25

26. In a mining apparatus, a frame, a supporting structure pivotally mounted on said frame to swing in a vertical direction with respect thereto, a cutter support pivotally mounted on said supporting structure to tilt relative thereto about an axis parallel with the supporting structure swing 30 axis, a horizontal plane kerf cutter carried by said cutter support, and means embodying extensible adjusting devices extending between and each connected at its opposite extremities to said frame and said cutter support for swinging said supporting structure and tilting said cutter support about their respective pivotal axes to move said kerf cutter into parallel horizontal cutting planes at different elevations, said swinging and means 35 also embodying means for locking said cutter support against tilting movement about its pivotal axis relative to said supporting structure during swinging of the latter and for locking said supporting structure against swinging movement about its pivotal axis relative to said frame during 40 tilting of said cutter support. 45

27. In a mining apparatus, a revoluble frame mounted for rotation about a horizontal axis, a supporting structure pivotally mounted on said frame, said frame being revoluble to position said supporting structure to swing in vertical and horizontal directions with respect thereto, a cutter support pivotally mounted on said supporting structure to tilt relative thereto about an axis parallel with the supporting structure axis, a horizontal plane kerf cutter carried by said cutter support, and means embodying extensible adjusting devices extending between and each connected at its opposite extremities to said revoluble frame and said cutter support for swinging said supporting structure and tilting said cutter support about their respective pivotal axes to move said kerf cutter into parallel cutting planes in either said horizontal or vertical positions of said supporting structure. 55

28. In a mining apparatus, a revoluble frame mounted for rotation about a horizontal axis, a supporting structure pivotally mounted on said frame, said frame being revoluble to position said supporting structure to swing in vertical and horizontal directions with respect thereto, a cutter support pivotally mounted on said supporting structure to tilt relative thereto about an axis parallel with the supporting structure axis, a horizontal plane kerf cutter carried by said cutter 70 75

support, and means embodying extensible adjusting devices extending between said revoluble frame and said cutter support and common to supporting structure swing and cutter support tilting for swinging said supporting structure and tilting said cutter support about their respective pivotal axes to move said kerf cutter into parallel cutting planes in either said horizontal or vertical positions of said supporting structure, said 10 swinging means also embodying means for locking said cutter support against tilting movement about its pivotal axis relative to said supporting structure during swinging of the latter.

29. In a mining apparatus, a revoluble frame 15 mounted for rotation about a horizontal axis, a supporting structure pivotally mounted on said frame, said frame being revoluble to position said supporting structure to swing in vertical and horizontal directions with respect thereto, a cutter 20 support pivotally mounted on said supporting structure to tilt relative thereto about an axis parallel with the supporting structure axis, a horizontal plane kerf cutter carried by said cutter support, and means embodying extensible adjusting devices extending between and each connected at its opposite extremities to said revoluble frame and said cutter support for swinging said supporting structure and tilting said cutter support about their respective pivotal axes to move 25 said kerf cutter into parallel cutting planes in either said horizontal or vertical positions of said supporting structure, said swinging and tilting means also embodying means for locking said cutter support against tilting movement about its pivotal axis relative to said supporting structure during 30 swinging of the latter and for locking said supporting structure against swinging movement about its pivotal axis relative to said frame during tilting of said cutter support.

30. In a mining apparatus, a swinging arm structure, a cutter support pivotally mounted on said arm structure for tilting movement relative thereto, a kerf cutter carried by said cutter support, and common motor operated devices having 35 common final terminal elements through which

arm structure swing and cutter support tilt are effected for swinging said arm structure and tilting said cutter support about its pivot relative to said arm structure to move said kerf cutter into parallel cutting planes, said devices for swinging said arm structure being operable independently of tilting movement of said cutter support about its pivot relative to said arm structure. 5

31. In a mining apparatus, a swinging arm structure, a cutter support pivotally mounted on said arm structure for tilting movement relative thereto, a kerf cutter carried by said cutter support, common motor operated devices for swinging said arm structure and tilting said cutter support about its pivot relative to said arm structure, 10 said arm structure to move said kerf cutter into parallel cutting planes, said devices for swinging said arm structure being operable independently of tilting movement of said cutter support about its pivot relative to said arm structure, and devices distinct 15 from said motor operated devices for locking said arm structure against swinging movement about its pivot during tilting of said cutter support and for locking said cutter support against tilting movement relative to said arm structure during 20 swinging of the latter. 25

32. In a mining apparatus, a rotatable head frame, a swinging arm structure pivotally mounted on said head frame, a cutter support pivotally mounted on said arm structure for tilting movement relative thereto, a kerf cutter carried by said cutter support, and common motor operated devices extending between said head frame and said cutter support having common final terminal elements through which arm structure swing and cutter support tilt are effected for swinging said arm structure and for tilting said cutter support about its pivot relative to said arm structure to move the kerf cutter into parallel cutting planes, said devices operative to effect 30 swinging of said arm structure independently of the tilting movement of said cutter support about its pivot relative to said arm structure. 35

CHARLES F. OSGOOD. 45

CERTIFICATE OF CORRECTION.

Patent No. 2,100,350.

November 30, 1937.

CHARLES F. OSGOOD.

It is hereby certified that error appears in the printed specification of the above numbered patent requiring correction as follows: Page 4, second column, line 66, claim 11, after the word "structure" insert a comma; page 6, second column, line 39, claim 26, after "and" insert tilting; and that the said Letters Patent should be read with this correction therein that the same may conform to the record of the case in the Patent Office.

Signed and sealed this 1st day of February, A. D. 1938.

(Seal)

Henry Van Arsdale,
Acting Commissioner of Patents.
